Primary Examiner — Kelley Donnelly(74) *Attorney, Agent, or Firm* — Notaro, Michalos & Zaccaria P.C.(57) **CLAIM**

The ornamental design for a basket, as shown and described.

DESCRIPTION

FIG. 1 is a front, left, top perspective view of a basket showing my design therefor;

FIG. 2 is a front elevational view, taken along line 6-6, the rear view being the mirror image;

FIG. 3 is a left side elevational view, the right side being the mirror image;

FIG. 4 is a top plan view thereof;

FIG. 5 is a bottom plan view thereof; and,

FIG. 6 is an enlarged cross sectional view showing the rim of the basket.
